UNITED STATES PATENT OFFICE.

HENRY G. LEISENRING, OF SAN DIEGO, CALIFORNIA.

PLATE-HOLDER FOR X-RAY EXPOSURES.

1,219,965.

Specification of Letters Patent. Patented Mar. 20, 1917.

Application filed May 2, 1916. Serial No. 94,960.

To all whom it may concern:

Be it known that I, HENRY G. LEISENRING, a citizen of the United States, residing at San Diego, in the county of San Diego and State of California, have invented certain new and useful Improvements in Plate-Holders for X-Ray Exposures; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to certain new and useful improvements in devices for taking a plurality of X-ray exposures on a single photographic plate and it has for its object to provide a device which will enable a physician to take one or more, preferably four, exposures in quick succession, of one part of a patient without moving said patient as is customary by use of machines now in use.

A further object of the invention is to provide a casing made of metal, the top covered by sheet lead, as is common in plate holders and which covering is impervious to X-rays, and having a central opening in the bottom and one in the top of the casing. The top opening is covered by a sheet of aluminum which is pervious to the X-ray, a plate holder containing a plate to be exposed being adapted to be moved longitudinally and laterally within the casing and under the opening so as to make four different exposures on said plate.

The invention comprises various details of construction, combinations and arrangements of parts which will be hereinafter fully described, shown in the accompanying drawings and then specifically defined in the appended claim.

My invention is illustrated in the accompanying drawings, in which:

Figure 1 is a top plan view of the invention.

Fig. 2 is a sectional view taken on line 2-2 of Fig. 1, and

Fig. 3 is a detail plan view of the plate holder shifting frame.

Reference now being had to the details of the drawings by letter, A designates a

box or casing, adapted to be supported by any suitable means, and is made of metal. This box comprises a top A' and bottom A², sides A³ and end wall A⁴, one end of said box being open as shown at A⁵. The top and bottom of said box are provided with centrally located openings B and B', rectangular in shape. A plate C of pervious material, such as aluminum, is fitted to cover the top opening B and is adapted to prevent any portion of the body of the patient from projecting through the opening B while said patient is being photographed.

A photographic plate D, which is to be exposed, is placed within a plate holder D' which in turn is placed within a suitable frame E for retaining the plate holder, and said frame has a handle E² extending from one end thereof to be grasped by the operator.

In operation, the person to be photographed is placed upon the casing with that part of the body to be photographed positioned directly over the plate C. The shifting frame E carrying the plate holder D' which contains the plate D is pushed through the open end A⁵ of the casing until its front edge is flush with the front edge of the casing, the side of the shifting frame being against the right side A³ of the casing. This position brings the forward left hand corner of the plate D under the exposure opening. An X-ray tube (not shown) is held directly over the opening B and patient and, when current is turned on, the rays will pass through the patient and aluminum plate C and photograph that portion of the body which lies over the opening. After the first exposure or number 1 is made, the frame may be quickly pushed straight back against the end A⁴ of the box. This movement will bring the section number 2 of the plate in position to be exposed, after which exposure the frame is moved to the left, thus bringing section number 3 in position and, when exposure is made of number 3, the frame is pulled forward until the edge of the plate holder is flush with the edge of the box and in this position section number 4 may be exposed.

It will thus be seen that four exposures may be quickly taken on a single plate. When it is desired to look through the patient before exposing the plate, it is only

necessary to remove the plate holder from the box and place the X-ray light tube beneath the box A.

What I claim to be new is:—

- 5 A device for taking X-ray photographs, comprising a metallic casing having a single open side, a covering of material, impervious to X-rays, upon the casing, said casing having registering openings in the opposite walls thereof, a plate of X-ray penetrable material placed over one of said wall openings, a plate holder adapted to retain

a sensitized plate therein, a handle adapted to be placed around said plate holder and projecting from the same, said plate holder 15 being adapted to be moved laterally and longitudinally within the casing to bring a plate carried thereby between said openings.

In testimony whereof I hereunto affix my signature in presence of two witnesses.

HENRY G. LEISENRING.
